US00D641736S

(12) **United States Design Patent**
Brunner et al.

(10) **Patent No.:** **US D641,736 S**
(45) **Date of Patent:** ** *Jul. 19, 2011

(54) **EAR BUD FOR AN AUDIO LISTENING SYSTEM**

(75) Inventors: **Robert Brunner**, San Francisco, CA (US); **Victoria Slaker**, San Francisco, CA (US)

(73) Assignee: **Beats Electronics, LLC**, Santa Monica, CA (US)

(**) Term: **14 Years**

(21) Appl. No.: **29/342,998**

(22) Filed: **Sep. 3, 2009**

(51) **LOC (9) Cl.** **14-01**

(52) **U.S. Cl.** **D14/223**; D14/205

(58) **Field of Classification Search** D14/205, D14/206, 223, 225, 226, 228, 142, 192, 218, D14/230; D13/133, 153, 154; 379/430, 379/433.03, 420.04; 381/380, 381; 181/129, 181/130, 135; D24/174; D2/606, 607; 455/90.3, 455/575.1, 575.2

(57) **CLAIM**

The ornamental design for an ear bud for an audio listening system, as shown and described.

DESCRIPTION

FIG. 1 is a perspective view of an ear bud for an audio listening system showing our new design;

FIG. 2 is a back view thereof;

FIG. 3 is a side view thereof;

FIG. 4 is an opposing side view thereof;

FIG. 5 is a front view thereof;

FIG. 6 is a top view thereof;

FIG. 7 is a bottom view thereof;

FIG. 8 is a perspective view of an ear bud for an audio listening system showing our new design, the only difference being the cord;

FIG. 9 is a back view thereof;

FIG. 10 is a side view thereof;

FIG. 11 is an opposing side view thereof;

FIG. 12 is a front view thereof;

FIG. 13 is a top view thereof; and,

FIG. 14 is a bottom view thereof.

The broken lines showing the environment in the Figures are for illustrative purposes only and form no part of the claimed design.

1 Claim, 4 Drawing Sheets
